HARD SURFACE FLOOR COVERING OR SIMILAR ARTICLE

Harry A. Shortway, Glen Rock, N. J., assignor to Con-goleum-Nairn Inc., Kearny, N. J., a corporation of New York

Application August 1, 1957, Serial No. 47,174

Term of patent 14 years

(Cl. D92—17)

The drawing is a plan view of a hard surface floor covering or similar article showing a full repeating unit between the margins thereof and marked to indicate the way in which the full repeating unit is constructed. The area beneath line 'ab' is repeated in half drop by the area to the right of line 'a'c' and beneath line 'a'b'.

I claim:

The ornamental design for a hard surface floor covering or similar article, substantially as shown and described.
